TIMBER SUPPORT FOR ROSSING MACHINES
AND THE LIKEJesse C. Cook, Jeffersonville, Ind., assignor to
American Creosoting Company, Louisville, Ky.,
a corporation of Delaware

Application June 25, 1934, Serial No. 732,362

8 Claims. (Cl. 144—208)

The present invention relates to timber supporting carriages for rossing machines or the like.

In rossing bark from large logs which are used in the production of telephone poles and the like, and machining the surface of the same, it is necessary to provide some means of support for the overhanging portions of the log, both as it is fed to and from the rossing machine. This support must travel with the log and must also permit the log to revolve as it passes through the machine.

An object of this invention is to provide an improved travelling supporting means in connection with a rossing or similar machine, for receiving and supporting the overhanging portion of a log as it is fed from the machine.

Another object is to provide such a support embodying log-supporting rollers which will permit rotation of the log and which are tiltably mounted on a supporting truck, whereby the log may be readily discharged to one side after it has passed through the rossing machine.

Other objects and advantages of the invention will become apparent during the course of the following detailed description of the invention when read in conjunction with the accompanying drawings, in which,

Fig. 1 is a side elevation showing a rossing machine in outline and the improved log-supporting means in operative position with respect thereto,

Fig. 2 is an end elevation of the log-supporting means, the dotted lines showing the supporting rollers in log-discharging position,

Fig. 3 is a side elevation of the log-supporting means, and

Fig. 4 is a perspective view of one of the skid bars.

Referring more particularly to the drawings, 5 indicates a track which extends in both directions from the rossing machine 6 and upon which the wheeled log-supporting carriages 7 are adapted to run back and forth for the purpose of supporting the overhang of the timber T as the same is fed to and from the rossing machine.

45 As shown more clearly in Figs. 2 and 3, the log carriages 7 consist of a base formed by horizontal channel irons 8 and 9 supported by the axles 10 of the flanged wheels 11. A pair of upright channel members 12 and 13 are mounted in spaced relation on the channel iron 8 and a pair of upright channel members 14 and 15, one opposite each of the members 12 and 13, are mounted on the channel iron 9. The channel members 12, 14 and 15 are braced and secured to the channel irons 8 and 9 by transversely extending

angle irons 16 and 17, respectively, which are welded or otherwise secured to both the horizontal and upright channel members. The channel members 12 and 13 are additionally braced by a gusset plate 18 welded to the same.

A pair of spaced transversely extending bars 19 and 20 are mounted between the upright channels 12, 14 and 13, 15, respectively. The bars are secured to the channel members, as by welding, and each is provided with a laterally inclined upper edge 21 extending from adjacent the center to one side of the carriage. The bars extend beyond the uprights 12 and 13 at that side so that the slanting surfaces 21 provide a skidway overhanging the side of the carriage.

A tilting log-cradle 22 is mounted between and supported by the bars 19 and consists of a pair of transversely disposed rollers 23 and 24 journaled on axles 25 between a pair of approximately triangular plates 26. The plates 26 are pivotally mounted upon a spindle 27 extending through openings 28 (see Fig. 4) in the bars 19 and 20. The rollers 23 and 24 are positioned at opposite sides of the spindle 27 and are preferably equally spaced therefrom, so that the load supported between the rollers will be balanced about the pivot provided by said spindle.

The axles 25 and spindle 27 are held in position against axial movement by small locking plates 29 which engage a groove or the like adjacent the ends thereof.

One corner of each of the plates 26 extends laterally beyond the uprights 14 and 15 and a handle 30, shown as a metal sleeve, is mounted between the extending portions upon a bolt 31. A stop 32 which may be formed of a piece of strap iron mounted between the uprights 14 and 15 serves to limit rotary movement of the cradle 22 in one direction and to position it for the reception of a locking pin 33 which passes through aligned openings in the uprights 14 and 15 and plates 26 to lock the cradle in normal position with the axes of the rollers 23 and 24 in substantially the same horizontal plane as shown in full lines in Fig. 2. A stop 34 which may be a wooden block mounted between the angle irons 16 is provided for engagement by the roller 24 to limit further tilting movement of the cradle when the upper surface of said roller has passed below the plane of the skidway provided by the inclined surfaces 21.

In the operation of the device, the cradle 22 is normally locked in the full line position of Fig. 2 by the locking pin 33 and as the log leaves the rossing machine, the overhanging end is 55

supported in the crotch of the rollers 23 and 24, thus permitting turning of the log during the feeding and rossing operation. After the log has completely cleared the rossing machine and is to be unloaded from the truck, the operator removes the locking pin 33 and lifts the handle 30. This operation results in rocking of the cradle about the pivot 27 to the dotted line position shown in Fig. 2 and lowers the log onto the slanting surfaces 21 of the bars 18. The rocking of the cradle in this manner imparts an initial transverse movement to the log and as it strikes the skids 21 it slides or rolls off to the side of the carriage, by gravity.

15 After the log has been discharged from the carriage, the operator pulls the cradle back to the normal position with the lower surfaces of the plates 26 engaging the stop 30 and inserts the locking pin, and the carriage is then ready 20 for the reception of another timber from the rossing machine.

It will be seen that due to the balancing of the load at all times, the operator can quickly 25 discharge the timbers from the truck with comparatively little effort, and delays in the rossing operation occasioned by failure to get the carriage back promptly into receiving position for the next timber are avoided.

While the carriage has been shown as dis- 30 charging to one side only, it will be understood that it could be made to discharge to either side; also that modifications and changes in details may be resorted to without departing from the spirit of the invention.

35 Also, it will be obvious that while the invention is especially applicable to the handling of logs, timbers and the like, it is equally useful in the supporting and discharging of any long, heavy articles, whether of wood, metal or other materials.

40 I claim:

1. A support for long, heavy articles such as 45 timbers, comprising a frame, a cradle pivotally mounted on said frame and adapted to support the article crosswise of the latter with the weight of the article balanced upon said pivot, a laterally inclined skidway mounted on said frame, and means permitting rocking of said cradle about its pivotal mounting to lower one side of the cradle to transfer the article to said skidway for discharge by gravity to one side of the support.

50 2. A wheeled carriage for use with rossing machines or the like for supporting the overhang 55 of timbers passing through said machine, having a tiltable timber supporting cradle pivoted about an axis substantially parallel to and substantially directly below that of the timber supported thereby and a laterally inclined skidway mounted thereon for receiving timbers from said cradle upon the tilting thereof to discharge them laterally of said carriage by gravity.

55 3. A carriage for supporting the overhang of timbers passing through a rossing machine or the like, having a wheeled body, transversely extending supporting bars mounted on said body in spaced relation, a timber supporting cradle pivotally mounted between said bars, said cradle comprising a pair of plate members pivotally 60 supported by and between said bars, rollers journaled between said plate members on either side of the pivotal mounting thereof and adapted to receive a timber therebetween, the upper surface of said bars providing a laterally inclined skidway below the supporting surface of said rollers

to receive a timber supported therebetween upon tilting of said cradle.

4. Means for supporting the overhang of a timber passing through a rossing machine or the like comprising a carriage, a tiltable cradle pivotally mounted transversely of the carriage, rollers journaled in said cradle on opposite sides of said pivot, means for locking said cradle against pivotal movement to maintain the horizontal axes of said rollers in substantially the same horizontal plane, and an inclined skidway adjacent one of the rollers so that upon tilting of said cradle a timber supported between said rollers will be discharged onto said skidway.

5. In an apparatus of the character described, 15 a carriage, a pair of transversely extending bars mounted on said carriage in spaced relation, a transversely tiltable cradle pivotally mounted between and supported by said bars, rollers journaled on said cradle on opposite sides of the pivotal mounting thereof and adapted to support a timber therebetween, said bars providing a laterally inclined skidway extending from adjacent one of said rollers to one side of said carriage for receiving an article supported by said rollers upon 20 tilting of said cradle to discharge said timber laterally of said carriage by gravity.

6. In an apparatus of the character described, 25 a carriage, a pair of transversely extending bars mounted on said carriage in spaced relation, a pair 30 of substantially triangular plates pivotally mounted between said bars, rollers journaled between said plates on opposite sides of the pivotal mounting thereof, said plates and rollers providing a cradle for an article, a handle mounted 35 between said plates for tilting the same, locking means for securing said plates in normal position with the axes of the rollers in substantially the same horizontal plane, said bars being provided with a laterally inclined upper surface extending 40 from adjacent one of said rollers to one side of said carriage, whereby the article supported between said rollers will be projected laterally onto said inclined surfaces and discharged by gravity 45 therefrom when said locking means is released and said plates are tilted about their pivotal mounting.

7. A support for long, heavy articles to be operated on and rotated during the operation, such as 50 logs, comprising a frame, roller members rotatable about axes substantially parallel to the axis of the article being supported and arranged to provide a crotch for seating said article, a supporting member having bearings for said roller members at said axes about which the same are 55 rotatable, said supporting member being pivoted in said frame about an axis parallel to that of the article and substantially directly below the same, to permit lowering of one of said roller members to discharge the article by gravity to 60 one side, and means for securing said supporting member in non-discharging position.

8. A support for long, heavy articles such as 65 logs or timber, comprising a frame, a member pivoted on said frame crosswise of the article about an axis substantially parallel to the axis of the article and substantially directly below the same, said pivoted member having supporting portions for the article on opposite sides of its axis and providing a crotch for holding said article between them in a substantially balanced condition, whereby when said pivoted member is tilted, the article will be discharged to one side by 70 gravity.
